(57) **CLAIM**

The ornamental design for a vacuum carafe, as shown and described.

DESCRIPTION

FIG. 1 is a front perspective view of a vacuum carafe showing my new design;

FIG. 2 is a top plan view thereof.

FIG. 3 is a right side elevational view thereof (the left side elevational view being a mirror image of the right side).

FIG. 4 is a front elevational view thereof.

FIG. 5 is a rear elevational view thereof.

FIG. 6 is a bottom plan view thereof.

FIG. 7 is a front perspective view of a vacuum carafe showing a second embodiment of my new design;

FIG. 8 is a top plan view thereof.

FIG. 9 is a right side elevational view thereof (the left side elevational view being a mirror image of the right side).

FIG. 10 is a front elevational view thereof.

FIG. 11 is a rear elevational view thereof.

FIG. 12 is a bottom plan view thereof.

FIG. 13 is a front perspective view of a vacuum carafe showing a third embodiment of my new design;

FIG. 14 is a top plan view thereof.

FIG. 15 is a right side elevational view thereof (the left side elevational view being a mirror image of the right side).

FIG. 16 is a front elevational view thereof.

FIG. 17 is a rear elevational view thereof.

FIG. 18 is a bottom plan view thereof.

FIG. 19 is a front perspective view of a vacuum carafe showing a fourth embodiment of my new design;

FIG. 20 is a top plan view thereof.

FIG. 21 is a right side elevational view thereof (the left side elevational view being a mirror image of the right side).

FIG. 22 is a front elevational view thereof.

FIG. 23 is a rear elevational view thereof.

FIG. 24 is a bottom plan view thereof.

FIG. 25 is a front perspective view of a vacuum carafe showing a fifth embodiment of my new design;

FIG. 26 is a top plan view thereof.

FIG. 27 is a right side elevational view thereof (the left side elevational view being a mirror image of the right side).

FIG. 28 is a front elevational view thereof.

FIG. 29 is a rear elevational view thereof; and,

FIG. 30 is a bottom plan view thereof.

The broken lines in the drawings are for illustrative purposes only and form no part of the claimed design.
